UNITED STATES PATENT OFFICE.

THOMAS A. BEANEY, OF POUGHKEEPSIE, NEW YORK, ASSIGNOR TO BEANEY RUBBER COMPANY, INC., OF NEW YORK, N. Y., A CORPORATION OF NEW YORK.

SHUTTLE AND BOBBIN FOR SEWING MACHINES.

Application filed June 24, 1924. Serial No. 722,051.

To all whom it may concern:

Be it known that I, THOMAS A. BEANEY, a subject of the King of Great Britain, and a resident of Poughkeepsie, Dutchess County, New York, have invented an Improvement in Shuttles and Bobbins for Sewing Machines, of which the following is a specification.

My invention relates to improvements in shuttles and bobbins for sewing machines, and more particularly to that type of sewing machine which has an oscillating shuttle and a bobbin held to turn in the shuttle and with relation to the shuttle. This structure is frequently used on sewing machines which have a bed in the form of an arm adapted to enter beneath flaps or hollow articles, such as boots and shoes. Heretofore the shuttle and bobbin used in a machine of this kind has been satisfactory because such machine has usually been run either by foot power, or at least at comparatively low speed. When, however, it is desired to use a machine of this kind at a high speed, difficulties arise because the high speed imparts so much momentum to the bobbin that when the shuttle is reversed in its oscillation, the bobbin continues for a sufficient space to cause the thread to be carried too far and eventually become tangled. On the other hand it is necessary that the bobbin have some little movement with relation to the shuttle, in order to facilitate threading and give the necessary flexibility in the stitching operation.

My invention is adapted to meet and overcome the above difficulties by providing a yielding brake for the bobbin which will give the desired flexibility referred to, and yet will hold the bobbin with sufficient tension to prevent it from being carried too far by momentum, even if the speed of the machine is very high.

I have used this structure in sewing loops to tire flaps, and I find that it greatly facilitates the work, and with the extension of the needle plate herein referred to, and the tension given to the bobbin, the machine may be run at very high speed, and consequently more work turned out on it than where the old style bobbin and shuttle are used. All of which will be better understood from the following description.

Reference is to be had to the accompany-

ing drawings forming a part of this specification, in which similar reference characters indicate corresponding parts in all the views.

Figure 1 is a broken perspective view showing the application of my invention to a machine of the kind referred to.

Figure 2 is an enlarged detail plan of the shuttle and bobbin.

Figure 3 is a cross section through the shuttle.

Figure 4 is a cross section showing a slightly modified form of the shuttle, and

Figure 5 is a cross section showing a kind of work to which the machine is well adapted.

The machine in general is of a well known type, the drawings indicating a common form of Singer sewing machine having the bed 10 in the form of an arm, and suitable needle bar mechanism 11. The needle plate 12 is pivoted on the top of the arm 10 and covers the shuttle as usual, but instead of terminating at the end of the arm as is customary, it is prolonged as shown in Figure 1 so as to readily enter a structure like 9, for instance, in Figure 5, and open the structure up so that the arm 10 can more readily receive it or enter it. The shuttle 13 and bobbin 14 are precisely as usual so far as their threading and operation are concerned, but the shuttle usually is in the form of a ring open at the bottom, and the bobbin 14 sits in it. In order that my improvement may be carried out, I preferably close the shuttle bottom as shown at 15, thus providing a convenient means for supporting the center post 16 which enters the hole 17 of the bobbin.

The post 16 affords a convenient means of flexibly braking the bobbin 14, and one way which I have tried and which is satisfactory, is shown in Figure 3, in which a ball 18 is held in a transverse socket 19 in the post, and is pressed outward by the spring 20. This bears against the wall of the hole 17 through the bobbin, and so when the shuttle 13 is oscillated, the ball 18 presses with sufficient friction to prevent the bobbin from turning too far at the reverse movement of the shuttle, and yet it leaves sufficient freedom of movement between the shuttle and bobbin to meet all requirements of the work.

Obviously the bobbin might be flexibly braked or given the required tension in

many ways. Another way from the above is illustrated in Figure 4. Here the post 16 is split vertically as shown at 21, thus giving to it a certain springiness, and if the 5 post is of a size which requires the separated members to be pressed slightly towards each other when the bobbin is placed over the post, the spring of the post members will accomplish the desired braking of the bobbin 10 and still give it the necessary flexibility. Doubtless the bobbin might be given the required tension in many other ways, but the illustrations serve to fully bring out the feature of my invention, to wit, the flexible

braking or tensioning of the bobbin with 15 respect to its containing shuttle.

I claim:—

The combination with an oscillating sewing machine shuttle having a center post to enter the bore of a bobbin, said post having 20 a transverse bore therein, of a spring pressed ball in said bore adapted to project into contact with the wall of the bobbin bore on said post.

In testimony whereof, I have signed my 25 name to this specification this 19th day of June, 1924.

THOMAS A. BEANEY.
